TIMING MODULATION SYSTEM

Earl I. Anderson, Manhasset, N. Y., assignor to
 Radio Corporation of America, a corporation of
 Delaware

Application March 19, 1943, Serial No. 479,738

10 Claims. (Cl. 179—171.5)

This application discloses a new method of and means for converting modulation frequency energy to timing modulated radio frequency energy. It uses a blocking type of oscillator and means is provided to insure that the blocking cycle of the oscillator always starts at the same point so that if the oscillator is considered as a generator only (in the absence of control potential) the generated frequency is stable. The blocking rate is controllable and in my system is controlled by signal currents or other control potentials. The blocking rate is the output frequency and thus variations in the blocking rate constitute frequency or timing modulation. The blocking rate may be varied over a wide range so that little or no frequency multiplication is necessary to achieve extensive deviation in the frequency or timing of the oscillations. It is advantageous to use as little frequency multiplication as possible in these systems because frequency instability is also multiplied in the same ratio. If the output frequency of the frequency modulated blocking oscillator is different from that desired for the output frequency of the system the blocking oscillator output may be heterodyned to the desired frequency. This heterodyning does not multiply the oscillator instability. Frequency correction means may be used to improve the oscillator stability in a manner well known in the art.

In describing my invention reference will be made to the attached drawings wherein the single figure illustrates the essential features of a modulation system arrangement in accordance with my invention.

In the figure T1 is a generator tube shown for the purpose of illustration as a triode having an anode and control grid regeneratively coupled by inductances L and L1. The cathode of this tube is connected to a point between resistors R3 and R4 in shunt to a source of direct current potential to raise the cathode of the tube T1 sufficiently positive with respect to ground to bias the same beyond cutoff. The grid of T1 is connected through inductance L1 to a point on the charging circuit for condenser C1. This charging circuit comprises the resistors R1 and R2 connected with a positive point of a source of potentials shown here as the source to which resistors R3 and R4 and the anode of T1 are connected. The tube T2 has its input electrodes coupled with a course of control potentials 10 and its anode connected through resistor R2 to the said source of potential. The condenser C1 is shunted by diode device 14.

1 The output of the oscillator, the operation of which will be described hereinafter, is fed by coupling condenser 20 and circuit 24 tuned to the generated frequency to the input grid 26 of a tube 5 T3. The tube T3 may be of the 6K8 or equivalent type having a triode section connected in an oscillation generating circuit including a tuned circuit 30 for the production of heterodyning oscillations which are mixed in the tube with the 10 generated oscillations fed to grid 26 to supply to the output electrode and output circuit 40 the sum or difference frequency as desired. The electron systems in tube T3 may be in separate envelopes. This output may also be supplied to a 15 mixer stage in 50 wherein it is beat against crystal controlled oscillations and fed to a discriminator and detector circuit to produce frequency control potentials which are fed to a control electrode of tube T2 by resistance 52.

20 Tube T1 and the inductances L and L1 form an oscillation circuit which except for modifications described hereinafter would operate in a known manner to generate oscillations of a frequency determined by the dimensions of L and 25 L1, etc. However, here the cathode of tube T1 is raised above ground by resistor R4 an amount in excess of cutoff bias. The charging potential supplied by R1 and R2 to C1 from the direct current source varies with the flow of current 30 through tube T2 and this in turn varies in accordance with the applied control or modulating potentials applied to the input electrodes of T2.

Assume that the tube T1 is biased to cutoff, control voltage is supplied to the tube T2 and the 35 current through this tube increases. As the voltage across C1 increases as a result of the current flowing through R1 and R2 the bias on the grid of tube T1 becomes less negative, i. e., decreases until tube T1 has sufficient Gm to start to oscillate, by virtue of the regenerative coupling including L and L1. The tube oscillates during the time which it takes to discharge condenser C1, this being a cycle in the blocking circuit operation.

45 The discharge path for the condenser C1 is through L1, T1 and R4—C5 in shunt. In other words, it is grid current to tube T1. But C1 can discharge only to zero potential and cannot be charged negatively because as soon as the cathode 50 of diode 14 becomes negative with respect to ground for an appreciable length of time the current flows through diode 14. In general it can be said that the charge on C1 cannot become negative with respect to ground but that C1 discharges 55 to zero at each cycle of operation and at this time

the grid of T_1 is most negative. (+ Bias on the cathode.)

Thus due to the action of the diode 14 the point at which discharge stops and charging starts is fixed, thereby fixing the starting cycle of the blocking oscillator and stabilizing the oscillations generated as to mean frequency.

When C_1 is discharged the control grid of T_1 is again biased to cutoff and C_1 begins to recharge and the process repeats at a rate determined by the rate of flow of current into C_1 . If under operating condition the maximum voltage across C_1 is small compared with the voltage at A and R_1 is fixed the charging rate of C_1 is determined by the voltage at A. This rate of flow of current into C_1 is determined or controlled by the output impedance of tube T_2 , the latter being determined by the control potentials of the grid of tube T_2 .

As has been explained the rate of flow of current to C_1 is controlled by T_2 and the rate at which T_1 operates is determined by the rate of current flow into C_1 (the length of time between cycles of operation of T_1 is dependent upon the length of time necessary for C_1 to charge to a voltage which overcomes the bias on T_1 and thus upon the rate of current flow into C_1). Thus the output frequency of T_1 is a function of the modulating frequency applied to T_2 and a frequency modulated signal is the result. Circuit 24 is tuned to the center frequency of the output from T_1 and is arranged to have the necessary band width to pass the frequency modulated signal.

The repetition rate frequency is then fed to the mixer tube T_3 in which it is heterodyned to the desired output frequency. Conventional circuit arrangements may be used in the automatic frequency control circuit including 50 and the control potential is derived by taking some of the output from tube T_3 and feeding it to unit 50 wherein it is amplified, changed in frequency, amplitude limited if desired and detected to derive a potential which changes when the mean frequency of the generated wave changes. This potential is fed out of 50 by way of resistor 52 to the control grid of the tube T_2 . The polarity of the potential is such that the plate current of tube T_2 is changed in a direction to act through the condenser C_1 to stabilize or counteract any changes in repetition rate in the blocking oscillator T_1 other than the changes in accordance with control potentials. The circuits in unit 50 for obtaining the control potential may be arranged as in Crosby U. S. Patents No. 2,279,659 and No. 2,279,660, or as in Seeley Patent No. 2,121,103.

As is usual in frequency modulated transmitters, the radio frequency amplifier stages following the modulated generator are arranged to limit amplitude modulation components in the output so that only frequency modulation is present in the output signal. For example, an amplitude limiter may be included in the coupling between tubes T_1 and T_3 or the limiting action may take place in a stage following tube T_3 .

I claim:

1. In a system of the class described, an oscillation generator tube having a control electrode biased beyond cutoff, a condenser and a charging circuit therefor, for applying a positive potential to said control electrode to overcome the said cutoff bias, and a discharge device in shunt to said condenser for preventing a negative charge from being built up thereacross for an appreciable period of time.

2. In a system of the class described, an energy

generator tube having a control electrode biased beyond cutoff, a condenser and a direct current charging circuit therefor, for applying a positive potential to said control electrode to overcome the said cutoff bias, and a diode connected in shunt to said condenser for preventing a negative charge from being built up thereacross for an appreciable period of time.

3. In a system of the class described, an oscillation generator tube having a control electrode biased beyond cutoff, a condenser and a direct current charging circuit therefor, for applying a potential to said control electrode to overcome the said cutoff bias, to cause said tube to generate energy and discharge said condenser, and a discharge device in shunt to said condenser for preventing a negative charge from being built up thereacross for an appreciable period of time.

4. In a system of the class described, an oscillation generator comprising a tube having electrodes regeneratively coupled, said electrodes including a control grid, means for biasing said control grid beyond cutoff, a condenser in a circuit including said control grid, a source of current for charging said condenser to overcome said negative bias whereby said tube becomes conductive to generate pulses and discharge said condenser, an electron discharge tube in shunt to said condenser, and means for controlling the rate of charge of said condenser to correspondingly control the rate of repetition of said charging and discharging of said condenser and as a consequence the rate of repetition of the pulses generated by said tube, comprising an electron discharge device having input electrodes and having output electrodes connected to said source of current, a source of modulation current coupled to the input electrodes of said discharge device, and a frequency stabilizing circuit coupling said generator to an electrode in said device.

5. In a system of the class described, an electron discharge device having an anode-like electrode, a cathode and a control grid coupled in an alternating current circuit, a direct current bias circuit connected to the grid and cathode of the device for biasing the device to cutoff, a condenser connected between said grid and cathode, an impedance and a source of direct current charging potential in a charging circuit for the condenser, the positive terminal of said source being adjacent to the terminal of the condenser coupled to the control grid so that when current flows through said impedance the charge on said condenser increases to reduce said cutoff bias so that the device becomes operative and the condenser discharges, means for controlling the current through said impedance in accordance with signals, and a discharge tube in shunt to said condenser to prevent a negative charge from building up thereon.

6. In a system of the class described, an electron discharge device having an anode-like electrode, a cathode and a control grid, a circuit regeneratively coupling the anode-like electrode and control grid of the device, a direct current bias circuit connected to the grid and cathode of the device for biasing the device to cutoff, a condenser connected between the grid and cathode of the device, an impedance and a source of direct current charging potential in series with the condenser with the positive end of the source connected to the side of said condenser coupled to the control grid, the arrangement being such that when current flows through said impedance the charge on said condenser increases to reduce

said cutoff bias so that the device oscillates by virtue of said regenerative coupling and the condenser discharges, means for controlling the current through said impedance in accordance with signals, and a diode in shunt to said condenser for limiting the extent to which the same can be discharged.

7. In a system of the class described, an electron discharge device having an anode-like electrode, a cathode and a control grid coupled in an alternating current circuit, a direct current bias circuit connected to the grid and cathode of the device for biasing the device to cutoff, a condenser connected between the control grid and cathode, an impedance and a source of direct current charging potential in a charging circuit for the condenser, the positive terminal of said source being adjacent to the terminal of the condenser coupled to the control grid so that when current flows through said impedance the charge on said condenser increases to reduce said cutoff bias so that the device becomes operative and the condenser discharges, a control tube having input electrodes excited by control potentials and having output electrodes connected by said impedance to said source of direct current, and a discharge tube in shunt to said condenser to prevent a negative charge from building up thereon.

8. In a system of the class described, an electron discharge device having an anode-like electrode, a cathode and a control grid coupled in an alternating current circuit, a direct current bias circuit connected to the grid and cathode of the device for biasing the device to cutoff, a condenser connected between the grid and cathode of the device, an impedance and a source of direct current charging potential coupled in series with the condenser with the positive end of the source connected to the side of said condenser coupled to the control grid, the arrangement being such that when current flows through said impedance the charge on said condenser increases to reduce said cutoff bias so that the device operates and the condenser discharges, means for controlling the flow of direct current through the impedance in accordance with signals, and a discharge tube in shunt to said condenser for limiting the extent to which the same can be discharged.

9. In a system of the class described, an electron discharge device having an anode-like electrode, a cathode and a control grid, a circuit regeneratively coupling the anode-like electrode and control grid of the device, a direct current bias circuit connected to the grid and cathode for biasing the device to cutoff, a condenser between said control grid and cathode, an impedance and a source of direct current charging po-

tential in a charging circuit for the condenser, the positive terminal of said source being adjacent to the terminal of said condenser coupled to the control grid of the device, a modulator tube having input electrodes excited by modulating potentials and having output electrodes supplied by direct current through said impedance, the arrangement being such that when current through said impedance to the output electrodes of said tube increases the voltage across said condenser increases to reduce the negative bias on said device so that the device oscillates by virtue of said regenerative coupling and the condenser discharges, connections to the input electrodes of said modulator tube for exciting said input electrodes in accordance with signals to control the current through said impedance in accordance with signals, and a diode in shunt to said condenser to limit the extent to which the same can be discharged.

10. In a system of the class described, an electron discharge device having an anode-like electrode, a cathode and a control grid coupled in an alternating current circuit, a direct current bias circuit connected to the grid and cathode of the device for biasing the device to cutoff, a condenser connected between said grid and cathode, an impedance and a source of direct current charging potential in a charging circuit for the condenser, the positive terminal of said source being adjacent to the terminal of the condenser coupled to the control grid so that when current flows through said impedance the charge on said condenser increases to reduce said cutoff bias so that the device becomes operative and the condenser discharges, a control tube having input electrodes excited by control potentials and having output electrodes connected through a portion of said direct current circuit to said source of direct current, and a discharge tube in shunt to said condenser to prevent a negative charge from building up thereon.
